(57) **CLAIM**

The ornamental design for a label for spooled wire products, as shown and described.

DESCRIPTION

FIG. 1 is a front elevational view of a label for spooled wire products showing my new design;

FIG. 2 is a perspective view;

FIG. 3 is a real elevational view; and,

FIG. 4 is a top plan view, which is identical to views from the bottom and both sides.

No claim is made to the wire basket shown in phantom outline which is shown for environmental purposes only.
